ART OF AUTOGRAPHING PHOTOGRAPHIC FILMS

Application filed February 24, 1930. Serial No. 436,487.

This invention relates to the art of autographing photographic films and has for its object the creation of an autograph in relatively light characters upon a relatively dark background in the negative and in relatively dark characters upon a relatively light background in the positive.

The present invention contemplates the creation of the autograph through the control of the development of the negative film in conjunction with the use of light, in such manner that the film is not subjected to light at any point except at the point of autographing and no foreign or deleterious matter can contact with or affect the film.

With the above and other objects in view, as will be apparent, this invention consists in the construction, combination and arrangement of parts, all as hereinafter more fully described, claimed and illustrated in the accompanying drawings wherein:

Fig. 1 is a fragmentary vertical section through one end of a camera taken transversely through an autographic opening in the case thereof, to illustrate the positions of the various elements during the autographing operation;

Fig. 2 is a perspective view of the frame coacting with the autographing table of the camera, for removably retaining a source of light and the element for controlling the development of the film, utilized in the form of the invention shown in Fig. 1;

Fig. 3 is a perspective view of the element for controlling the development of the film;

Fig. 4 is a similar perspective view of the light panel or source of light utilized in the form of the invention shown in Fig. 1;

Fig. 5 is a fragmentary vertical section through one end of a camera, taken transversely through the autographic opening in the case thereof to illustrate the positions of the various elements during the autographing operation using a modified form of the present invention;

Fig. 6 is a perspective view of the element used in the form of the invention disclosed in Fig. 5 for controlling the development of the film at the autographic panel similar in

construction and operation to the controlling element illustrated in Fig. 3;

Fig. 7 is a fragmentary elevation of a section of the film used in the form of the invention illustrated in Figs. 5 and 6 showing the same in conjunction with the paper back, parts of the latter being broken away for the purpose of illustration;

Fig. 8 is a fragmentary vertical section through one end of a camera, taken transversely through the autographic opening in the case thereof, to illustrate the positions of the various elements during the autographing operation, using another modified form of the present invention;

Fig. 9 is a fragmentary elevation of a section of film showing the paper backing thereof used in the form of the invention shown in Fig. 8, parts being broken away;

Fig. 10 is a vertical longitudinal section taken through the film illustrated in Fig. 9 and used in the form of the invention used in Fig. 8;

Fig. 11 is a perspective view of the element which controls the development of the film used in the form of the invention disclosed in Figs. 9 and 10 similar in construction to those illustrated in Figs. 3 and 6;

Fig. 12 is an elevation of a fragment of a negative film produced by the use of the present invention illustrating the autograph thereon; and

Fig. 13 is a similar view of the positive print reproduced from the negative shown in Fig. 12 utilizing the present invention and illustrating the autograph thereon.

In all of the forms of the invention, forming the subject matter hereof, the space between exposures hereinafter called the autographic panel is utilized for the purpose of making the autograph. Fundamentally the invention consists in affecting the entire autograph panel or space between exposures with light and then tracing the autograph upon the panel in such manner that those portions of the panel corresponding to the characters of the autograph will be undeveloped, or at least the development thereof will be retarded, when the negative film is developed. Thus the negative film will have a light struck

or black field throughout the entire autograph panel surrounding relatively clear or light characters. When reproduced the field will appear white or relatively light upon the positive print and the characters surrounded thereby will be black or relatively dark.

Reference being had more particularly to the drawings 10 designates the negative film having the autograph panel or space between exposures 11; one such panel being provided for and adjoining each exposure space. The film is provided with the usual paper back 12.

The camera used in carrying out each form of the present invention consists of a case 13 having an autographing opening 14 therein, through which the autograph may be traced or inscribed on the paper back 12 of the film. This autograph opening 14 is designed to be closed by a gate 15, hinged to the case 13, of the camera, when the autograph opening 14 is not being used for the purpose of creating an autograph. Opposed to the opening 14 is an autographing table 16 upon which rests the film during the act of tracing or inscribing the autograph and which carries certain of the elements to be hereinafter described entering into the autographing operation. The film spool 17 is positioned in the camera case 13 from which the film 10 and its paper back 12 is fed to the take-up spool (not shown). In passing from the spool 17 to the take-up spool the film 10 and its paper back 12 pass between the wall of the camera case 13 containing the autograph opening 14 and the table 16. The mechanism and parts above described are common to all forms of the invention illustrated herein.

In the form of the invention illustrated in Figs. 1 to 4 inclusive, the autographing table 16 is covered by a retaining frame plate 18, provided with an aperture 19 therein which corresponds to the surface of the table 16 and defines the space available for autographic purposes. The longitudinal sides of this frame plate 18 are provided with the arms 20 which engage the edges of the autographing table 16 and retain the plate 18 thereon. Between the table 16 and the frame plate 18 are positioned the elements which control the development of the autographic panel of the film and effect the same by light. The first of these elements, to-wit; that element adjoining the table 16 is a light plate 21 having its outer surface 22 coated with any suitable radio-active material. This light plate may be made of metal, celluloid or any other suitable material and the coating may be of any chemical compound capable of radiating actinic rays, such as compounds containing radium or radium salts or their compounds. An example of such a compound would be phosphorescent zinc sulphide containing a small percentage of radium or radium salts. Exteriorty of the luminous plate 21 is the control sheet 23

which controls the development of the autograph panel of the film or at least the development of those portions corresponding to the inscribed or traced autograph. This control sheet 23 comprises a translucent sheet of paper or other suitable material, impregnated with wax or grease or any other chemical or compound which may be transferred to the film as hereinafter described and which will retard or prevent development of such portions of the film to which it has been transferred and covers.

The operation of the form of the invention shown in Figs. 1 to 4, inclusive, is as follows: The body of the film 10 to receive the exposure is positioned within the camera 13 above the table 16 while the autograph panel or space between exposures 11 of the film 10 is aligned with the opening 14 and the table 16. During the entire time that the panel 11 is thus situated the light rays from the plate 21 pass through the control sheet 23 and act upon the sensitized surface of the panel 11. When the stylus or other writing implement 24 is inserted through the autograph opening 24 to inscribe or trace an autograph upon the back 12 of the film 10, the pressure exerted thereby causes the film to be pressed against the surface of the control sheet 23. This writing pressure exerted while tracing or inscribing the autograph upon the outer face of the back 12 transfers the material with which the control sheet 23 is impregnated, to the sensitized surface of the film. Thus the autograph appears on the sensitized surface of the film in characters removed or transferred from the control sheet 23, of the material with which said sheet is impregnated. The film is then wound upon the take-up spool and the process is repeated until the entire roll of film is used.

It will be observed that at no point beyond the plane of the table 16 does any light contact with the film for the purpose of autographing. When the film is developed the portions of the panel 11 surrounding the characters of the autograph will be fully and completely developed while the emulsion beneath the characters or beneath the material removed or transferred from the control sheet 23 will remain wholly or at least very greatly undeveloped, so that when the negative film 10 is washed and dried the autograph will appear in relatively clear or light characters surrounded by a relatively dark field.

The characters of the autograph being traced on the sensitized surface of the film in a material which will retard or entirely overcome the development of the emulsion beneath the coating will be reproduced in the negative film merely by constituting spaces or gaps in the developed emulsion surrounding them. It will also be observed that after

the autograph has been traced on the panel 11 and the film is wound upon the take-up spool, the material in which the characters of the autograph are traced does not contact with the sensitized surface of the film but on the contrary are opposed to the plain or unsensitized surface thereof.

In the form of the invention disclosed in Figs. 5, 6 and 7 the luminous plate 21 is eliminated. In this form of the invention the autograph panels 11 of the film 10 are exposed to light prior to winding the film 10 and back 12 upon the spool 17 and prior to its insertion in the camera. This exposure of the autograph panels 11 to the action of light may, of course, be done by the manufacturer of the film during the process of manufacture. When the panel 11 is positioned over the table 16 upon which a control sheet 23 is held in place by the frame plate 18, as described in Fig. 1, the inscribing of the autograph by means of the stylus or other writing implement 24 will remove from the control sheet 23 the material with which it is impregnated and trace characters of the autograph on the sensitized surface of the film in this material as above described. When the film is then developed, the development of the characters of the autograph will be retarded or eliminated, and the autograph appears in relatively light characters surrounded by a relatively dark field.

In the form of the invention shown in Figs. 8 to 11 the paper back 12 is translucent throughout its entire length. Between those portions 26 of the back 12 corresponding to the autograph panels 11 of the film, the back is coated as at 25 with an opaque compound such as lamp black mixed with gelatin containing some glycerine or any other material which will render the back 12 light-proof. Thus the back 12 of the film 10 is light-proof except as to those portions 26 which correspond to the autographic panel 11. Thus when the autographic panel 11 is positioned in alignment with the opening 14 and table 16, light admitted through the opening 14 will pass through the corresponding translucent section 26 at the back 12 and affect the sensitized surface of the film. Then when the stylus or other suitable writing implement 24, is used to inscribe or trace the characters of the autograph upon the back 12 the material with which the control sheet 23 is impregnated will, as heretofore described, be transferred to the sensitive surface of the film and retard or stop development of those portions thereof which it covers or contacts with. Thus the autograph is created on the negative film 10 in clear or relatively light characters surrounded by a relatively dark field.

From the foregoing it is manifest that all forms of the present invention accomplish the creation of the autograph in the panel or

space between exposures by means of exposing the entire panel to light and then retarding or stopping development of such portions thereof as correspond to or constitute the autograph. It is also apparent that light does not affect the sensitized surface of the film 10 at any points except at the panels 11 and that the sensitized surface of the film is at all times protected from contact with foreign or deleterious matter.

The control sheet 23, being detachable may be from time to time replaced, as the material impregnating it becomes exhausted. Of course a control sheet 23 may accompany each film roll and can be placed under the frame plate 18 when the camera is loaded with the film.

What is claimed is:

1. The method of autographing a photographic film consisting in exposing one portion of the film to create an image and exposing another portion thereof to light and retarding or preventing the development of parts of such last exposed portion.

2. The method of autographing a photographic film consisting in exposing a portion thereof to light while in a camera and coating the sensitized face of said exposed portion in a design corresponding to the autograph with a material that will retard or prevent development of the sensitized surface covered thereby.

3. The method of autographing a photographic film within a camera consisting in exposing to light the portion thereof between exposures, and coating the sensitized base of said exposed portion, in a design corresponding to the autograph, with a material that will retard or prevent development of the sensitized surface of the film covered thereby.

4. The method of autographing a photographic film within a camera consisting in exposing to light the portion thereof between exposures, and coating the sensitized base of said exposed portion by pressure from the exterior of the camera, in a design corresponding to the autograph, before development with a material that will retard or prevent development of the sensitized surface of the film covered thereby.

5. The method of autographing a photographic film while in a camera consisting in exposing to light that portion thereof known as between exposures, coating the sensitized face of said exposed portion prior to development, in a design corresponding to the autograph with a material that will retard or prevent development of the sensitized surface of the film covered thereby.

6. The method of autographing a photographic film having a paper back while in a camera, consisting in exposing that portion of the film known as between exposures to the action of light, outlining the autograph.

on the paper back, and coating the sensitized face of the exposed portion of the film in the outline of the autograph with a material that will retard or prevent development of the sensitized surface covered thereby.

7. The method of autographing a photographic film having a paper back, consisting in exposing that portion of the film known as between exposures to the action of light, 10 outlining the autograph with pressure on the paper back at a point corresponding to the exposed portion of the film, and coating the sensitized face of the exposed portion of the film by the pressure outlining the autograph 15 with a material that will retard or prevent development of the sensitized surface covered thereby.

8. The method of autographing a photographic film having a paper back while in 20 a camera, consisting in exposing that portion of the film known as between exposures to the action of light, outlining the autograph on the paper back by pressure at a point corresponding to the exposed portion of the film, 25 and coating the sensitized face of the exposed portion of the film with a material that will retard or prevent development of the sensitized surface covered thereby by means of the pressure exerted on the paper back in outlining the autograph aforesaid.

9. The combination with a camera having an opening in the wall thereof, of a table aligned with said opening and spaced from the wall of the camera whereby the film and 35 its back pass between the table and opening, a luminous plate secured to said table, and a control sheet disposed above said luminous plate for transferring material to the film to retard or prevent the development thereof.

10. The combination with a camera having an opening in the wall thereof, of a table within the camera opposed to said opening and spaced from the wall of the camera to permit the film and its back to pass between 45 the table and said opening, an actinic ray emitting plate secured to said table to affect the section of film positioned in alignment with the table and opening and a control sheet disposed above said actinic ray-emitting plate impregnated with a material to be transferred to the sensitized surface of the film by pressure exerted through the opening aforesaid upon the back of the film, said material retarding or preventing development of those portions of the sensitized 55 film covered thereby.

11. The combination with a camera having an opening in the wall thereof, of a table within the camera opposed to said opening 60 and spaced from the wall of the camera to permit the film and its back to pass between the table and said opening, an actinic ray-emitting plate coacting with said table, a control sheet disposed above said plate and 65 impregnated with a material to be transferred

to the sensitized surface of the film by pressure on the back of said film through said opening to prevent or retard the sensitized surface covered thereby, and a frame plate secured to said table for retaining the control sheet and plate in position.

12. The combination with a camera having an opening in the wall thereof, of a table within the camera opposed to said opening and spaced from the wall of the camera to permit the film and its back to pass between the table and said opening, an actinic ray-emitting plate coacting with said table to affect that portion of the film aligned with the opening and table, a control sheet disposed above said plate and impregnated with a material to be transferred to the sensitized surface of the film by pressure on the back of said film through said opening to prevent or retard the development of the sensitized surface covered thereby, and a frame plate removably secured to said table for retaining the control sheet and plate aforesaid in position thereon.

13. In a camera, the combination with 90 means within the camera for light affecting a predetermined portion of a film, of a source of material to prevent or retard development of the film, and means for transferring said material to parts of said predetermined portion 95 of the film.

14. In a camera, the combination with 100 means within the camera for light affecting a predetermined portion of a film therein, of a source of material to retard or prevent development of the sensitized surface of the film, and means for transferring said material to part sensitized surface of that portion of the film affected by light by the means aforesaid.

15. In a camera, the combination with 110 means within the camera for light affecting a predetermined portion of a film therein, of a source of material within the camera for retarding or preventing the development of the sensitized surface of the film, and means for transferring said material to that portion of the film affected by light by the means aforesaid in a pattern or designation through pressure on the unsensitized side of the film.

16. In a camera the combination with 120 means for light fogging a portion of a sensitized film therein, of means for placing material on the sensitized surface so fogged to prevent or retard the development of portions thereof.

17. The combination with a camera, of an actinic ray emitting panel positioned to light strike a portion of each section of a film located for exposure, means whereby a pressure may be exerted on said panel in the form of an inscription or design, and means, coacting with said panel for transferring a development retarding medium upon the sen- 125

sitized surface of the film by the pressure aforesaid.

18. The combination with a camera, of an actinic ray emitting panel positioned to light strike a portion of each section of a film located for exposure, means whereby a pressure may be exerted on said panel in the form of an inscription or design, and means, coacting with said panel, for transferring a development retarding agent to the sensitized surface of the light struck portion of the film by the pressure aforesaid.

19. The combination with a camera, having an autographing opening in one wall thereof through which an autographic pressure may be exerted on the backing of a film within the camera, of an actinic ray emitting panel within the camera facing the sensitized surface of a film within the camera and opposed to said opening, whereby the autographing pressure causes the sensitized surface of that portion of the film aligned with the opening to be light struck, and means for outlining the autograph in a development retarding agent on that portion of the film light struck by the rays emitted by the panel aforesaid.

20. The combination with a camera, having an autographing opening in one wall thereof through which an autographing pressure may be exerted on the backing of a film within the camera, of an actinic ray emitting panel within the camera facing the sensitized surface of a film within the camera and opposed to said opening, whereby the autographing pressure causes the sensitized surface of that portion of the film aligned with the opening to be light struck, and a control sheet interposed between the panel and the sensitized surface of the film for transferring a development retarding agent to the film in the form of the autograph by the autographing pressure.

21. The combination with a camera, having an autographing opening in one wall thereof through which an autographing pressure may be exerted on the backing of a film within the camera, of an actinic ray emitting panel within the camera facing the sensitized surface of a film within the camera and opposed to said opening, whereby the autographing pressure causes the sensitized surface of that portion of the film aligned with the opening to be light struck, and a translucent control sheet placed over said panel to transfer a development retarding agent to the sensitized surface of the film by the autographing pressure.

JOHN P. SCANNELL.
